[57] CLAIM

The ornamental design for a sink, as shown and de-
scribed.

DESCRIPTION

FIG. 1 is a perspective view taken from the top, front
and right side of a sink showing our new design;

FIG. 2 is a top plan view thereof;

FIG. 3 is a cross-sectional view taken on line 3—3 of
FIG. 2;

FIG. 4 is a cross-sectional view taken on line 4—4 of
FIG. 2;

FIG. 5 is a cross-sectional view taken on line 5—5 of
FIG. 2;

FIG. 6 is a cross-sectional view taken on line 6—6 of
FIG. 2;

FIG. 7 is an enlarged fragmentary cross-sectional view
taken on line 7—7 of FIG. 2;

FIG. 8 is an enlarged fragmentary cross-sectional view
taken on line 8—8 of FIG. 2; and,

FIG. 9 is an enlarged fragmentary cross-sectional view
taken on line 9—9 of FIG. 2.

The broken line representation of holes and the frag-
mentary broken line representation of a counter top in
FIG. 1 are for purposes of illustration only and form no
part of the claimed design.
